UNITED STATES PATENT OFFICE.

MAURICE GEVERS, OF ANTWERP, BELGIUM.

APPARATUS FOR REFINING LOAF-SUGAR.

SPECIFICATION forming part of Letters Patent No. 717,838, dated January 6, 1903.

Application filed July 19, 1902. Serial No. 116,178. (No model.)

To all whom it may concern:

Be it known that I, MAURICE GEVERS, manufacturer, a subject of the King of Belgium, residing at Antwerp, in the Kingdom of Belgium, have invented certain new and useful Improvements in Apparatus for Refining Loaf-Sugar, of which the following is a specification.

The different methods of refining loaf-sugar at present in use present considerable inconvenience, the conical shape of the loaf producing much waste when cutting up the sugar, or the inefficient manner in which the masse-cuite is submitted to the action of the cleare, which acts alternately or simultaneously on the hardest and on the most porous part of the substance, according to the process employed, and, in addition, the complication of the material employed, to which it was inevitable to have recourse hitherto in order to obtain rectangular tablets, owing to the difficulties encountered in removing these tablets from the molds, the said material possessing besides its complexity the serious inconvenience of allowing large quantities of cleare to pass freely through without useful effect during the expulsion of the green syrup.

In the annexed drawings, which represent a form of apparatus suitable for carrying out the invention, Figure 1 is a plan view, partly in section, of a box for forming the cakes. Fig. 2 is an elevation thereof. Fig. 3 is a vertical section of the centrifugal, showing the boxes in their places therein for the operation of decoloring. Fig. 4 is a plan view, partly in section, of said centrifugal. Fig. 5 is a front view, on a larger scale, of one of the recesses or chambers for receiving the boxes. Fig. 6 is a corresponding horizontal section.

In order to prevent waste of the conical cakes, they are molded in the boxes 1, presenting the shape of a parallelepiped rectangle, and to prevent waste of cleare produced in the boxes of this kind already known and those provided with plates and combs intended to facilitate the subsequent removal of the cakes these parts are dispensed with and the masse-cuite allowed to flow direct into the boxes, which are supplied with special means, hereinafter described, for permitting the removal of the cakes after the decoloring. As shown in Figs. 1 and 2, these means con-

sist, essentially, in forming the box 1 in two parts 2 and 3, each forming one side and one end of the box, and arranging them exactly 55 one against the other at diagonal edges 4 and giving said two parts a suitable rigid connection—for instance, by means of a clamp 5, provided with tenons 6, each entering a corresponding groove 7, provided in the two adjacent vertical faces of the parts 2 and 3. The tenons 6 are preferably slightly conical for producing a certain tension in the connection. The clamps 5 are in addition provided on each side with tongues 8 to determine the exact placing in position and entering of the parts 2 and 3. Each of these parts is provided on its interior upper parts with grooves 10 for reception of iron plates or partitions 11, determining the thickness of 70 the cakes. These partitions 11 can be arranged, as shown in Fig. 1, across the width of the box in proportion to its length, according to the required size of the cakes to be produced. Each box is provided at its upper part with a rim 9, having a preferably conical edge 12, Fig. 2, the corresponding part of each clamp 5 also having a part of this kind, so that each of the boxes is provided for the whole of its circumference with a conical border the purpose of which will be explained hereinafter. The centrifugal apparatus employed in combination with these boxes is similar in general to the apparatus generally used—that is, it has an exterior 85 drum 13, into which a perforated basket 14 is placed for reception of the boxes containing the solidified masse-cuite. This drum is put in motion by a shaft 15, operated in any convenient manner. This shaft, however, 90 traverses the drum for its entire height, for purposes which will be explained below, and has bearing in a bracket 16, situated outside the apparatus, above the basket 14. According to this invention the basket 14 is provided 95 exteriorly with a series of recesses or chambers 17, each serving to receive a box. These recesses are produced by the uprights 18 occupying the free space existing between two adjacent boxes 1, placed in the basket, and by the cross-pieces 19, placed at the bottom of the basket, and cross-pieces 20, connecting the interior edges of uprights 18 at their upper part.

In the example represented two uprights or adjacent parts form, in conjunction with the cross-pieces 19 and 20, a rectangle or framing for each box, as shown in Fig. 5. The 5 uprights 18 and the cross-pieces 19 and 20 present an inclined surface 21, in which is a groove for reception of india-rubber or other elastic material 22 of rectangular section, constituting packing on which the conical part 10 12 of each box rests after its introduction into the recess formed by the uprights 18 and the cross-pieces 19 and 20. In practice the cross-pieces 19, forming in the center of the centrifugal a regular octagon, (when the basket 15 is intended to hold eight boxes,) can be fixed by any convenient means at the bottom of the basket, and the cross-pieces 20 can be bolted, for example, to the uprights 18, which may be formed in one with the basket and 20 can be attached to it.

Between two concentric uprights 18 and 25 against the outside walls of the basket at the bottom of each recess are placed perforated plates 23, forming a movable bottom to the boxes, the construction of which is well known. Above the cross-pieces 20 is fixed—for instance, by bolts 24—a plate or circular cover 25, (shown in plan view in Fig. 4,) extending toward the center of centrifugal at a certain 30 distance above the inner edges of boxes 1 to prevent the cleare flowing above the recesses 17 or the boxes contained therein on rotation of the basket. This cover 25 is provided at its part adjacent to basket 14 with openings 35 26 to permit the perforated plates 23 to be easily taken out and replaced.

In order that the invention may be clearly understood, the working of the process and the method of employing the turbine will now 40 be described in detail.

To fill the boxes 1, a certain number are placed one above the other, the bottom part of each resting on the edge 9 of the box immediately below, preferably after interposition 45 of an india-rubber ring or other suitable substance between two successive boxes. The masse-cuite is then left to cool in the superposed boxes. It is obvious that since the masse-cuite flows in the same manner into the 50 different boxes all the latter after solidification of the mass will have the most porous part (or foot) at the side where the border 9 is and that one will not have, as when employing conical boxes, the porous part of the 55 mass (foot) and the hardest part (head) alternately at the same part of two successive boxes. When the masse-cuite is solidified, the boxes are transferred to the centrifugal. Owing to the extension of the shaft 15 through 60 basket 14, the latter has in its central part between the inner edge of plate 25 and said shaft 15 an open space 27 large enough for the introduction of the boxes, which are then each introduced horizontally into the recesses 65 or chambers 17 in such a manner that the edge 12 bears slightly against the rubber packing 22, placed in the groove of the frame formed

by the uprights 18 and cross-pieces 19 and 20. In this position the boxes do not extend to the perforated plates 23 at their exterior sides next to the rim of basket 14, nor do they come in contact with these plates until the centrifugal has been put in motion, and the centrifugal force which tends to push them back outwardly forces the boxes to press 70 the packing 22 by the conical edges 12. After a box has been placed into each of the chambers of the centrifugal the liquoring takes place in the latter without slackening the speed. It is evident that the cleare cannot find any other passage except across the boxes, each of the latter effecting through the rotation of the centrifugal an automatic joint or packing in its recess, as will be understood. On the other hand, in each box itself the 80 cleare will not find a free passage, as was the case before when using boxes provided with plates and combs, since the masse-cuite adheres directly to the walls of the boxes in the present case. The liquoring terminated, the 85 boxes are taken out of their recesses, and it is then a question of removing the tablets from the boxes. To attain this, it is sufficient to withdraw the two clamps 5 by sliding them vertically with their tenons 6 in the 90 grooves 7 of the walls 2 and 3 by hand or a suitable tool, as indicated by arrow 28 in Fig. 2. On the clamps being withdrawn the box is divided into two parts 2 and 3, and the tablets or cakes are withdrawn at the same time 95 as the partitions 11. A very simple method of taking the cakes from their molds is thus obtained without any waste, and, on the other hand, it is obvious that owing to the arrangements described all the objects aimed at and 100 referred to at the beginning of this specification are obtained, and all loss of cleare is prevented in the centrifugal, due to placing the boxes into recesses in which they form a perfect joint. The masse-cuite is always present- 105 to the action of the cleare at the most porous part, while the green syrup is regularly expelled from the hardest or head part of the mass. In fact, no loss of cleare whatever can take place in the boxes themselves, these admitting no plate which could form with the so-called "walls" of the boxes passages through 110 which cleare could escape without exercising its useful effect.

In the description above described the connection of two parts of the boxes has been 115 represented as being effected by special clamps. It is, however, evident that we do not intend to confine ourselves to this kind of connection or to the construction described 120 of the recesses or basket of the centrifugal, as these can be either made in one with the basket or constructed by means of the several 125 separate pieces connected into a suitable shape.

What I claim is—

1. The box to be used on centrifugal machines formed of two parts each forming one side and one end of the box and a rigid con-

nection holding the two parts together substantially as described and for the purpose set forth.

2. The box to be used on centrifugal machines formed of two parts, each forming one side and one end of the box, a rigid connection between the two parts of the box and a rim 9 at the upper part of the box, substantially as described and for the purpose set forth.

3. The box to be used on centrifugal machines formed of two parts each forming one side and one end of the box, a clamp, tenons provided on said clamp, grooves provided in the two vertical faces of the parts of the box and in which the said tenons are adapted to engage and a rim provided with a conical edge at the upper part of the box and clamp, substantially as described and for the purpose set forth.

4. A box to be used on centrifugal machines consisting of a frame open at both its ends and having a rim extending around one end to form a seating-flange, substantially as described.

5. A box to be used on centrifugal machines comprising a rectangular frame in two pieces each piece being made up of a side and an end and removable clamps at the diagonally opposite joints, each clamp having tenons fitting in grooves in the frame-piece and being removable by a sliding movement of the clamps in a direction longitudinally of the joint, substantially as described.

In witness whereof I have hereunto set my hand in presence of two witnesses.

MAURICE GEVERS.
